HAIR CURLER

Gabriel Boulard, Paris, France

Application May 20, 1937, Serial No. 143,643

9 Claims. (Cl. 132—33)

This invention relates to a hair curler that is of the type that is used for permanently waving hair. By this invention the hair is heated in such close proximity to the bulb of a thermometer that the thermometer responds promptly to the temperature which the hair reaches and thereby makes provision for enabling the operator to avoid overheating the hair either by observing the position of the mercury column in the stem of the thermometer or by having the mercury column in this stem automatically cut off the heat that is being applied to the hair.

The invention will be understood from the description in connection with the accompanying drawing, in which Fig. 1 is a side view of an illustrative embodiment of the invention; Fig. 2 is a similar view taken at right angles to Fig. 1; Fig. 3 is a longitudinal section along the line 3—3' of Fig. 2; and Fig. 4 is a section along the line 4—4' of Fig. 3.

In the drawing, reference character 1 indicates a glass tube that is adapted for having a lock of hair wound thereon which is to be curled or waved. This tube is of smaller diameter at an intermediate portion, as indicated at 2, where the hair is wound upon it, and gradually increases in diameter on both sides of this smaller portion. This tube 1 terminates at one end thereof in a cylindrical portion 3 that is preferably smaller in diameter than the diameter of the largest part of this tube. The end of the cylindrical portion is closed as indicated at 4 and the other end is closed as indicated at 5. A metal band 6, that may be corrugated transversely if desired, is applied near the end 5 and may be kept in place by any suitable sort of heat resisting cement.

A metal sleeve 7 surrounds the cylindrical portion 3 of the tube 1 and its inner end that contacts with the shoulder joining the cylindrical portion 3 to the main portion of the tube 1 is made in the form of a band 8 that may be corrugated transversely if desired. The sleeve 7 is cemented to the cylindrical portion 3 by any suitable heat resisting cementitious material and a window or opening 9 is provided in this sleeve 7 for a purpose to be described.

A handle 10 of insulating material, which may be somewhat oval shaped in transverse section, is provided with a stem 11 which extends into the sleeve 7 and may contact with the end 4 of the portion 3. This handle 10 may also be cemented in the sleeve 7 by suitable cementing material. A pin 12 is also passed through the sleeve 7 and stem 11 to keep the parts assembled.

The bulb 13 of the thermometer that is used in this device consists in part of the smaller diameter portion of the glass tube 1 with the end of this bulb made up of a conically shaped closure member 14 that may be fused or otherwise securely attached to the inside surface of the tube 1. The upper end of the bulb 13 terminates in a somewhat similar member 15 which is, however, provided with a hole at the center and is attached there to a hollow stem that is provided with a spiral portion 16 and a straight portion 17 into which the mercury rises when the bulb is heated, the upper portion of the mercury column being visible through the opening 9 in the sleeve 7. The mercury in the bulb is indicated by 19 and 15 upon being heated rises in the capillary hole 18 of the stem of the bulb, which is graduated in a suitable manner.

A cap 20 having one end dove-tail shaped fits into a corresponding recess in the handle 10 and a screw 21 holds this cap normally in place. Semi-circular recesses 22 are provided in the contacting faces of the cap 20 and handle 10 for receiving electric wire plugs 23 and 24 that are provided with binding screws 25 and 26 for attaching wires 27 and 28 thereto. These wires 27 and 28 pass through holes in the handle 10 and stem 11 and terminate in the capillary hole 18 in the stem 17 of the thermometer, as indicated at 29 and 30 respectively, these wires being sealed in place where they pass through the wall of the stem. A plate 31 is provided in the portion 3 of the tube 1 and transverse lines 32, 33 and 34 are provided on this plate in position to be visible through the window 9. This plate is installed behind the stem 17 and the lines 32, 33 and 34 indicate the temperature ranges within which the temperature should be while the device is operating. Line 34 is preferably made red to warn the operator that the temperature is dangerously high. The terminals 29 and 30 are located so that when the mercury rises in the stem to the danger point a circuit is closed between the wires 27 and 28. The terminals 22 are adapted to receive a plug of a circuit (not shown) of a well known sort in which a source of current and an alarm is provided, so that when the mercury rises enough in the stem 11 to close the contact between the wires 27 and 28, the alarm will be sounded.

I claim:

1. A hair curler comprising a hollow portion of rigid heat resisting material for having hair wound thereon, a thermometer bulb in said hollow portion, and a sleeve for supporting said hollow

50

55

portion and surrounding a portion of the stem of said thermometer.

2. A hair curler comprising a hollow portion of rigid heat resisting material for having hair

5 wound thereon, a thermometer bulb in said hollow portion, a sleeve for supporting said hollow portion and surrounding a portion of the stem of said thermometer, and a handle of insulating material for said sleeve.

10 3. A hair curler comprising a hollow portion for having hair wound thereon, a thermometer bulb in said hollow portion, a sleeve for supporting said hollow portion and surrounding a portion of the stem of said thermometer, a handle of insulating material for said sleeve, electric terminals in said handle and electric wires from said terminals extending into the inside of said stem.

15 4. A hair curler comprising a hollow portion for having hair wound thereon, a thermometer bulb in said hollow portion, a sleeve for supporting said hollow portion and surrounding a portion of the stem of said thermometer, a handle of insulating material for said sleeve, electric terminals in said handle and electric wires from said terminals extending into the inside of said stem at different points longitudinally thereof.

20 5. A hair curler comprising a glass tube and a thermometer having a portion of the wall of

25

5. A hair curler comprising a glass tube and a thermometer having a portion of the wall of

said tube constituting the wall of the bulb of said thermometer.

6. A hair curler comprising a glass tube and a thermometer having a portion of the wall of said tube constituting the wall of the bulb of said thermometer, the stem of said thermometer being spiral for a portion of its length.

7. A hair curler comprising a glass tube and a thermometer having a portion of the wall of said tube constituting the wall of the bulb of said thermometer, the stem of said thermometer being spiral for a portion of its length, and electric wires terminating inside of said stem.

8. A hair curler comprising a glass tube and a thermometer having a portion of the wall of said tube constituting the wall of the bulb of said thermometer, and a metal sleeve surrounding another portion of said glass tube.

9. A hair curler comprising a glass tube and a thermometer having a portion of the wall of said tube constituting the wall of the bulb of said thermometer, the stem of said thermometer being spiral for a portion of its length, and a metal sleeve around said stem provided with an opening through which a portion of said stem is visible.

GABRIEL BOULARD.
